ABSTRACT OF THE DISCLOSURE

A portion of a paper making machine is disclosed where paper stock discharged from a headbox is deposited upon a Fourdrinier type web forming wire provided with drainage foil assemblies beneath the wire (substituted for table rolls), and a foil assembly is supported beneath the wire by a support mechanism carried on rails beneath and parallel to the edges of the wire. The assembly includes a body which is connected to the support mechanism and a foil cap mounted on top of the foil body. The foil body and foil cap are of special design providing a spring loaded dovetail connection between the foil body and foil cap.

CROSS-REFERENCE TO RELATED PATENT APPLICATION

A mechanism, for adjusting the angle of a foil relative to the bottom surface of a Fourdrinier wire, is disclosed in this application and which is the subject of our copending U.S. patent application entitled Angularly Adjustable Support Mechanism for Fourdrinier Drainage Foil, Ser. No. 672,118, filed Oct. 10, 1967

BACKGROUND OF THE INVENTION

Field of the invention

This invention relates to paper making machines having drainage foils, deflectors, forming boards or the like, beneath a Fourdrinier type web forming wire and in particular to a foil assembly including a body carrying a removable and replaceable foil cap beneath the Fourdrinier wire.

Description of the prior art

A concept involved in this invention is that of providing blades, now commonly called drainage foils, beneath a Fourdrinier wire in the position formerly occupied by table rolls, to achieve superior drainage of water through the bottom of the wire. The evolution of this concept to present day forms is illustrated by the following patents: British Pat. 399,739 in 1933; British Pat. 717,798 in 1954; U.S. Pat. 2,744,454 in 1956; U.S. Pats. 3,017,930 and 3,027,941 in 1962; U.S. Pat. 3,140,225 in 1964; and U.S. Pats. 3,165,440 and 3,201,308 in 1965. In all of these prior art arrangements some provision is made for replacing a foil after it has become worn but with a considerable variation in the speed and convenience of such replacement.

SUMMARY OF THE INVENTION

It is a primary object of the present invention to provide a new and improved drainage foil assembly for promoting water removal through the bottom of a Fourdrinier web forming wire.

Another object of the present invention is to provide a drainage foil assembly or the like with a new and im-

2

proved arrangement for quickly replacing a removable cap.

Another object of the present invention is to provide a new and improved arrangement for mounting a removable foil cap on a body supported below the bottom surface of a Fourdrinier wire.

According to a preferred embodiment of the present invention, a Fourdrinier wire drainage foil assembly includes a body portion supported in a generally horizontal position below a Fourdrinier wire, with a foil cap mounted on top of the foil body. The foil cap is attached to the body by a dovetail tongue and groove type joint. The dovetail tongue is defined by the bottom surface of the foil cap and projects downwardly. The top surface of the foil body defines a portion of the dovetail groove including a generally horizontal groove bottom surface and one groove wall angularly inclined upwardly from the bottom surface in a direction to be partly over the bottom surface. A flexible strip spring is connected to the body adjacent the groove surface on the opposite side thereof from the one groove wall defined by the foil body. The strip spring is arranged to project upwardly from the groove bottom surface and is inclined toward the one groove wall defined by the body. The strip spring therefore provides a second groove wall and thereby completes the formation of a dovetail groove complementary with the tongue of the coil cap. The strip spring is biased toward the groove wall defined by the body and therefore firmly holds the dovetail tongue of the foil cap but allows easy withdrawal and insertion of the tongue through an open end of the slot.

Other features and objects of the invention that have been attained will appear from the more detailed description of an embodiment of the invention shown in the accompanying drawings.

BRIEF DESCRIPTION OF THE DRAWING

FIG. 1 is a diagrammatic side elevation view of a portion of a paper making machine showing a portion of a headbox, a breast roll, Fourdrinier wire and drainage foil assemblies according to the present invention;

FIG. 2 is an enlarged and fragmentary view of one of the drainage foil assemblies of FIG. 1, showing the assembly in greater detail and partly in section taken along line II—II of FIG. 1; and

FIG. 3 is a view partly in section taken along line III—III in FIG. 2.

DESCRIPTION OF THE PREFERRED EMBODIMENT

Referring to the drawing and FIG. 1 in particular, a portion of a paper making machine is shown wherein a headbox 1 discharges pulp through a slice opening 2 to deposit the pulp on a Fourdrinier wire 3 as it leaves a breast roll 4 that is turning in the direction indicated by the arrow. A plurality of drainage foil assemblies 5 are shown arranged beneath the wire 3 and mounted on side rails 6.

Referring to FIG. 2, the foil support assembly 5 is shown as having a lower support member 10, an upper support member 11 that may be raised and lowered by a threaded post 12 carried on top of support member 10 and secured to rail 6 by a bolt 13, a foil body 14, and a foil angle adjusting mechanism 15 connecting foil body 14 to upper support member 11. A replaceable foil cap 16 is mounted on top of the foil body in a manner that

will appear as the description of the disclosed apparatus proceeds.

The foil angle adjusting mechanism 15 includes a pair of vertical plates 30, 31. Plate 30 is adjacent foil 14 and is attached thereto. Plate 31 is adjacent upper support member 11 and is attached to that member. The two plates 30, 31 have vertical surfaces that engage in a vertical plane A—A and cooperate to define therebetween a mated key 32 and keyway 33. As shown in FIG. 2, in the preferred embodiment the key 32 projects from plate 30 into a keyway 33 in plate 31. The key 32 may however project from plate 31 into a keyway 33 in plate 30. As shown in FIG. 3 the configuration of the key and keyway 32, 33 is arcuate with a radius R emanating from a point on an axis coincident with the leading knife-edge 34 of foil cap 16. The term "leading" as herein used to describe knife-edge 34 refers to the orientation shown in FIG. 1 where it is shown that the knife-edge 34 is the lead edge with respect to the approach of wire 3 toward foil cap 16.

The foil angle adjusting mechanism 15 also includes a variable length link assembly 40 pivotally connected on one end to the vertical plate 31 by any suitable means, such as for example a shaft 46 mounted to rotate relative to plate 31. The other end of assembly 40 includes a bolt 50 that projects through a slot 51 in plate 31 to plate 30 where an end portion 52 of bolt 50 is threadingly attached to plate 30. The slot 51 in plate 31 is oriented (see FIG. 3) to present its major axis C—C generally perpendicular to a radius R' from a point on leading edge 34.

The foil cap 16 is attached to the foil body 14 by a dovetail tongue and groove type joint that will now be described. As shown in FIG. 2 a dovetail tongue 17 is formed on the bottom of foil cap 16 and has a generally horizontal surface 18, a first tongue wall 19 spaced back of the leading knife-edge 19, to define therebetween the downwardly projecting dovetail tongue 17. A third wall 21 defined by cap 16 is spaced back to the second wall 20 and cooperates therewith to define a slot 22. The tongue walls 19, 20 are inclined downwardly in diverging relation to each other to form with the surface 18 the dovetail tongue configuration 17. A portion of a dovetail groove 23 is defined on top of said foil body 14 by a generally horizontal surface 24 and a groove wall 25. A flexible strip spring 26 is attached to the foil body 14 by cap screws 27. The strip spring 26 projects upwardly from groove surface 24 in converging relation to wall 25 and into slot 22. Wall 25, surface 24 and strip spring 26 complete the formation of a dovetail groove 23 in foil body 14 which is complementary to dovetail tongue 17 and the spring 26 is biased toward wall 25 to firmly hold tongue 17 and foil cap 16 in position relative to foil body 14 and Fourdrinier wire 3.

In the operation of the described apparatus the position of the foil assembly 5 along rail 6 may be adjusted by loosening bolts 13 and then sliding lower support member 10 along rail 6 until assembly 5 is at a desired location. If it is desired to adjust the vertical position of foil 14 relative to wire 3, the bolt 13 is first loosened. Post 12 may then be turned to project downwardly a greater distance below upper support 11 which has the effect of raising support 11 and attached structures, relative to lower support 10 and wire 3. Turning post 12 to project downwardly a lesser distance below support 11 of course will lower support 11 and all structures carried thereby. When post 12 has been turned to carry foil 14 at the desired level relative to wire 3 and/or assembly 5 is moved to a desired location on rail 6, then bolt 13 is tightened to secure the apparatus in position.

The angular tilt of foil 14 relative to wire 3 may be adjusted independently of any adjustments such as have been described and may or may not have been performed. To adjust the angular tilt of foil 14 bolts 50 and 53 are first loosened. Then the adjustable length link assembly

40 is adjusted to change the effective length of the link assembly 40. If, from the position shown in FIG. 3, assembly 40 is adjusted to increase the effective length of assembly 40, the end portion 52 of bolt 50 will move plate 30 and attached foil 14 relative to plate 31 and attached support 11. Key 32 and keyway 33 will guide this movement to be pivotal clockwise (as seen in FIG. 3) and about the axis coincident with the leading knife-edge 34 of foil cap 16. Shortening link assembly 40 will pivot plate 30 and attached foil 14 counterclockwise (as seen in FIG. 3). The pivotal movement in either clock direction will however be about the axis coincident with leading knife-edge 34 of foil cap 16 and the position of edge 34 relative to Fourdrinier wire 3 will not change. Thus the described pivotal adjustment of foil 14 cannot inadvertently bring knife-edge 34 in a position that may expose the foil 14 to excessive wear or cause the edge 34 to cut the Fourdrinier wire 3.

In time the top surface of the foil cap 16 and its leading knife-edge 34 will become worn and require replacement. To remove the cap 16 it is merely withdrawn endwise, i.e., to the left or right as shown in FIG. 2. A replacement cap is then mounted on the body 14 by inserting tongue 17 into the dovetail groove 23 and sliding the cap 16 along the top of the body until it is centered thereon.

From the foregoing detailed description of the present invention it has been shown how the objects of the invention have been attained in a preferred manner. However, modifications and equivalents of the disclosed concepts such as readily occur to those skilled in the art are intended to be included within the scope of this invention. Thus, the scope of this invention is intended to be limited only by the scope of the claims such as are or may hereafter be appended hereto.

The embodiments of the invention in which an exclusive property or privilege is claimed are defined as follows:

1. Fourdrinier wire drainage foil assembly and the like including a pair of elements one of which is a foil body adapted for support in a generally horizontal position and the other of which is a cap mounted on top of said body and connected thereto, said body having a top surface and said cap having a bottom surface cooperating to define therebetween a dovetail tongue and a portion of a dovetail groove, said portion of said dovetail groove including a generally horizontal groove surface and a first transverse groove wall, and a flexible strip spring connected adjacent said groove surface on the opposite side thereof from said first groove wall and with said strip spring projecting away from said groove surface in a direction converging toward said first groove wall to provide a second wall for said groove and thereby define a dovetail groove complementary engaging said dovetail tongue, and said strip spring being biased toward said first groove wall to removably engage and firmly hold said dovetail tongue therebetween.

2. A drainage foil assembly according to claim 1 in which said dovetail tongue projects downwardly from the bottom surface of said foil cap, said portion of said dovetail groove is defined in the top of said foil body, and said flexible strip spring is connected to said body to complete the formation of a dovetail groove in said body complementary to said dovetail tongue projecting from said foil cap.

3. A drainage foil assembly according to claim 2 in which said foil cap has a leading knife-edge and said tongue projecting from said foil cap is spaced away from a vertical plane through said leading knife-edge; said tongue is defined by a generally horizontal surface, a first transverse tongue wall spaced in close proximity from said vertical plane, and a second transverse tongue wall remote from said vertical plane; a third transverse wall defined by said foil cap is spaced from said second wall in a direction away from said tongue; and said second

3,515,636

5

tongue wall and said third wall cooperate to define a slot into which said strip spring projects to provide complete complementary engagement of the dovetail groove with the dovetail tongue.
